CARTRIDGE FEED MECHANISM FOR FIREARMS

Ferenc Gebauer, Budapest, Hungary, assignor of one-half to "Danuvia" Ipari és Kereskedelmi R. T., Budapest, Hungary, a firm of Hungary

Application August 4, 1937, Serial No. 157,233
In Hungary April 28, 1937

4 Claims. (Cl. 89—33)

It is known that, in rapid firing firearms, only a very short time is available for feeding the cartridges from the belt or magazine into the chamber of the barrel. Moreover the cartridges undergo during this feeding movement a number of changes of direction, sudden alterations of speed and concussions which give rise to unforeseen and harmful movements particularly oscillation and resonant phenomena, that very often endanger the reliable operation of the firearm. The oscillation phenomena that occur in known cartridge feed mechanisms result from the cartridges not being sufficiently firmly gripped during their passage from the magazine to the chamber, so that the cartridges can perform secondary movements in the intermediate members, which movements are harmful even if they be of short duration. The period during which the cartridges are being withdrawn from the belt or magazine is particularly critical, since the cartridge extractor for example moves together with the breech block and undergoes the same accelerations as the breech block. Acceleration is imparted to the breech block at the instant of firing and the cartridge extractor draws the cartridge out of the magazine or belt as the breech opens, that is to say at the time of greatest acceleration. Another critical time is when the cartridge, after it has been moved a suitable distance from the magazine or belt, has to have its direction of movement reversed to enable it to be thrust into the firing chamber.

Attempts have been made to remove this disadvantage, for instance by means of an arrangement in which the cartridge extractor moves together with the breech block and causes the cartridge, after it has been withdrawn from the belt or magazine, moved a suitable distance away from the barrel and the cartridge extractor has been lifted out of engagement with the rim of the cartridge, to impact against a rear wall provided on the pivoted carrier of the cartridge feed mechanism; from this position the cartridge is thrust into the chamber of the barrel by the forwardly moving breech block. With this arrangement, however, troubles have also been experienced due to the constantly increasing and extremely high rates of fire employed at the present time. These troubles are mainly due to the fact that the cartridge is caused to impact against the rear wall of the pivoted carrier and that it is removed from this position by the forwardly moving breech block with considerable impact so as to enable it to be thrust into the chamber.

The present invention has for its object to provide a cartridge feed mechanism which operates reliably even with higher rates of fire than have been employed hitherto and which safely conveys the cartridges without shock or impact from the magazine or cartridge belt to the barrel.

According to the present invention the cartridge extractor is actuated through a lever system by a movable part of the breech block mechanism, for example by the breech block, with a velocity lower than that of the breech block itself, and withdraws the cartridges out of the belt or magazine, conveys them firmly gripped into the opening of the chamber and then transfers them for the completion of the feed movement into the chamber—to the forward moving breech block.

A constructional embodiment of the cartridge feed mechanism according to the present invention is illustrated in the accompanying drawings in which:

Fig. 1 shows the cartridge feed mechanism of a machine gun in longitudinal section in the position which it occupies when the breech is closed.

Fig. 2 is a similar longitudinal section, but with the breech fully open.

Fig. 3 is another similar longitudinal section, the breech block being, however, in the position it occupies when it takes over the function of cartridge feeding from the cartridge extractor.

Fig. 4 is a diagrammatic plan view of the belt feeding mechanism, and,

Fig. 5 is a section on the line V—V of Fig. 1.

In the drawings, 1 represents a cartridge, 2 a part of the machine gun casing, 3 the cartridge belt, 4 the barrel, 5 the chamber of the barrel and 6 the breech block (Fig. 1).

The breech block 6 is connected by means of a link 7 to a control lever 8 which is mounted for pivotal movement about a pivot pin 18. The link 7 is connected to the breech block 6 by a pivot pin 41 and to the control lever 8 by a pivot pin 19. When the breech block moves first rearwardly and then forwards, the control lever 8, due to its connection as described above, is also rocked first rearwardly and then forwards. A locking spring 25 presses against a pivot pin 21 on the control lever 8, and a cartridge extractor 10 and a drag link 22 are connected at one end to pivot pins 9 and 20 respectively.

At the operative end of the cartridge extractor 10 there is provided a claw 11 which, when the breech block occupies its front end position, engages the rim of the cartridge 1 to be withdrawn

from the cartridge belt 3. The claw 11 of the cartridge extractor is pressed against the cartridge in this position by a pressure pawl 15 which is loaded by means of a spring 17 contained in a 5 guide socket 16. The other end of the spring 17 presses against the machine gun casing, and the pressure pawl 15 is mounted for pivotal movement about a pivot pin 14 in a pivoted carrier 13, so that it drops or rises with the latter. On each side of 10 the cartridge extractor 10 close to the claw 11 is formed a guide stud 28. On rearward movement of the breech block 6, the claw 11 withdraws a cartridge from the cartridge belt guided by the two studs 28, it draws the cartridge into pivoted 15 carrier 13 in which are formed guide grooves 29 for the studs 28 (see Fig. 5). The pressure pawl 15 is of such a length that the rearwardly moving cartridge extractor 10 remains under the action thereof until the studs 28 reach the guide grooves 20 29 (Fig. 5), thus ensuring that the claw 11 of the cartridge extractor does not become disengaged from the cartridge. The guide grooves 29 are located at such a distance from the guide chamber 31, which is adapted to receive the cartridge, that 25 the cartridge is held securely by the claw 11 (Fig. 1). The function of cartridge feeding is later taken over from the claw 11 by a nose 30 on the cartridge extractor 10. The claw 11 continues to draw the cartridge along with it as long as the 30 breech block is moving rearwardly. Meanwhile the cartridge extractor is freed from the action of the pressure pawl 15 and the latter then presses directly on the cartridge 1 (Fig. 2).

The pivoted carrier 13 rocks in the machine gun about a pivot pin 42. When the breech block 6 moves rearwardly and the cartridge extractor 10 has withdrawn the cartridge 1 from the belt 3, the pivoted carrier rocks under the action of the spring 17 already referred to into its lowermost position, which is limited by an abutment 35 37 on which the pivoted carrier 13 rests by means of its abutment surface 38. The pivoted carrier 13 however is pressed down into its lowermost position not only by the spring 17, but also by a 40 cam surface 43 on a slider 23. The slider 23 is actuated by the control lever 8 through a link 22 which is connected to the slider by a pivot pin 42. The slider 23 performs a rectilinear forward and rearward movement in guides 24 formed in the 45 casing of the machine gun, which movement is however shorter than that of the breech block. As the cartridge 1 leaves the feed block, the cam surface 43 comes into contact with a surface 39 on the pivoted carrier 13 and, as it slides over this 50 surface, first presses the pivoted carrier 13 down about its pivot pin 42 and then, after it has reached its lowermost position, holds it down in this position by means of a surface 40. Owing to this constructional arrangement, firstly the spring 55 11 can be made relatively weak, so that the pivoted carrier is not liable to become distorted by the pressure of the spring when extracting a cartridge, and secondly the pivoted carrier is secured in its lowermost position against harmful movements and rebound shocks.

The cartridge that has been drawn into the guide chamber 31 in the pivoted carrier 13 is not released by the cartridge extractor 10, but is supported by the nose 30 and gradually braked, just 60 as the rearwardly moving parts of the locking spring 25 are gradually braked and brought to rest. The breech block 6 and the parts connected thereto are likewise returned from their rearmost positions by the locking spring 25, the latter 65 serving gradually to accelerate the breech block 70

6 and the cartridge 1 which rests against the nose 30 of the cartridge extractor 10 (Fig. 3). As soon as the nose of the bullet enters the chamber 5, the cartridge assumes a position in which it can leave the guide chamber 31. The lower part of 5 the guide chamber facing the barrel is cut out and, as the rim of the cartridge reaches this part, the pressure pawl 15, which presses on the cartridge 1 and is loaded by the spring 17, ejects the cartridge 1 from the guide chamber 31. Thus the 10 cartridge 1 is freed from the action of the nose 30 of the cartridge extractor and the breech block 6 advancing rapidly from behind the cartridge 1 thrusts the latter entirely into the chamber 5 of the barrel 4.

As soon as the cartridge 1 is removed from the pivoted carrier 13, the latter moves rapidly into its uppermost position. This movement is brought about as the breech block moves forward by a slide 23 which is moved by means of the link 22. To this end a tappet 26 on the slide 23 moves beneath a cam surface 27 on the pivoted carrier 13 and, as it moves forward, raises the latter. While the breech block moves forward the belt has to be advanced by one cartridge. The slide 25 23 moves forwards and rearwards along guides 24 (Fig. 4) under the action of the control lever 8. Connected to a pin 32 on the slide 23 is a link 33 which with the aid of a bell crank lever 34 reciprocates the feed slide 36 along guides 35. During 30 each movement of the slide 23 in the direction B, the belt is drawn forward by one cartridge by means of the feed slide 36. As soon as the advance of the belt finishes, the rockable member 13 and the cartridge extractor 10 move into the uppermost position, the claw 11 snaps over the rim of the cartridge and the extraction of the cartridge can begin again (Fig. 1).

The accelerations of the cartridge 1, the slide 23 and the locking spring 25 are smaller than that of the breech block 6, since the radial distances between the pivot 18 of the control lever 8 and the points of connection 9, 20, 21 of the members which move the cartridge 1, slide 23 and locking spring 25 are smaller than the distance between 45 from the pivot 18, and the pivotal connection 19 of the link 7 which is connected to the breech block 6. These accelerations moreover differ at the cartridge and at the slider owing to the fact that the points of connection 9 and 20 of the members which move the corresponding parts do not lie 50 in the straight line 18, 19, but make an angle therewith. The size of this angle and its position relative to the straight lines 18, 19 may differ as required from those shown in the drawings.

The control lever 8 and the link 7 form with the pivot pins 41, 19, 9 and with the pivot 18 the retarding lever system by means of which the breech block 6 actuates the cartridge extractor 10, to which lever system may be added the link 22 60 and pivot pins 20, 42 by means of which the breech block 6 actuates the feed slide 23. The locking spring 25 and the pivot pin 21 which connects the spring to the control lever 8 may also be regarded as forming part of the same lever system.

The straight lines, which on the one hand connect the point of connection of the breech block to the control lever 8 and on the other hand the point of connection of the lever with the pivot 18, enclose an angle between them.

The constructional embodiments described above may be considerably modified as far as constructional and operating details are concerned, without changing the invention itself. In general all the parts may be replaced by equivalent parts.

The breech block may consist of a plurality of parts; the movement of the belt may be obtained in any other manner; and the cartridges may be fed from a cartridge magazine instead of from a cartridge belt.

Having now particularly described and ascertained the nature of my said invention, and in what manner the same is to be performed, I declare that what I claim is:

- 10 1. In a rapid fire machine gun, the combination of a cartridge extractor moved by a part of the breech block mechanism and having a cartridge-engaging end provided with an extracting claw and a pushing nose, a lever system connecting 15 said part of the breech block mechanism to said cartridge extractor mechanism and comprising a pivoted control lever, and two pivot pins connecting said control lever one to the breech block mechanism and the second to the cartridge extractor mechanism, the angle between the line 20 connecting the first pivot pin to the pivot of said control lever and the line of movement of the breech block when the breech block is in closed position being smaller than the angle between the line connecting the second pivot pin and the pivot 25 of said control lever and said line of movement.

2. In a rapid fire machine gun, the combination of a cartridge extractor moved by a part of the breech block mechanism and having a cartridge-engaging end provided with an extracting claw and a pushing nose, a lever system connecting 30 said part of the breech block mechanism to said cartridge extractor mechanism and comprising a pivoted control lever, two pivot pins connecting 35 said control lever one to the breech block mechanism and the other to the cartridge extractor mechanism, the angle between the line connecting the first pivot pin to the pivot of said control lever and the line of movement of the breech block 40 when the breech block is in closed position being smaller than the angle between the line connecting the second pivot pin and the pivot of said control lever and said line of movement, and a slider connected by pivot pins and by a link to said lever system to bring about the feed movement of the cartridge belt.

3. In a rapid fire machine gun, the combination of a cartridge extractor moved by a part of the breech block mechanism and having a cartridge-

engaging end provided with an extracting claw and a pushing nose, a lever system connecting said part of the breech block mechanism to said cartridge extractor mechanism and comprising a pivoted control lever, two pivot pins connecting 5 said control lever one to the breech block mechanism and the other to the cartridge extractor mechanism, the angle between the line connecting the first pivot pin to the pivot of said control lever and the line of movement of the breech block 10 when the breech block is in closed position being smaller than the angle between the line connecting the second pivot pin and the pivot of said control lever and said line of movement, a slider connected by pivot pins and by a link to said lever 15 system to bring about the feed movement of the cartridge belt, a pivotally mounted cartridge carrier, a tappet on said slider, a control surface on said pivoted carrier, said control surface being adapted to be engaged by said tappet as soon as 20 the cartridge has been extracted from the magazine or belt, said tappet sliding along said control surface and depressing the pivoted carrier about its pivot, a second control surface on the pivoted carrier, this control surface being adapted to be 25 engaged by said tappet to hold the pivoted carrier in the depressed position, a second tappet on the slider, and a third control surface on the pivoted carrier, this control surface being adapted to be engaged from below by said second tappet on the 30 slide as soon as the cartridge has been pushed out of the pivoted carrier, said second tappet thereby raising the pivoted carrier.

4. In a rapid-fire machine gun, the combination with a breech-block mechanism of a cartridge 35 extractor, a decelerating lever pivoted on a fixed fulcrum and pivotally connected with said breech-block mechanism and said cartridge extractor, the distance between the fulcrum of said lever and the point thereof to which the breech-block is connected exceeding that between said fulcrum and the point to which said cartridge extractor is connected, and a pivoted carrier to guide the cartridge extracted by said extractor from the magazine or belt into the opening of the barrel chamber, 40 thereby enabling the breech-block to push the cartridge into said chamber.

FERENC GEBAUER.
